CLAIM

The ornamental design for a PC mouse docking station, as shown and described.

DESCRIPTION

FIG. 1 is a top, right, and rear isometric view of the PC mouse docking station, according to my new design.

FIG. 2 is a top, right, and front isometric view of the PC mouse docking station of FIG. 1.

FIG. 3 is a top plan view of the PC mouse docking station of FIG. 1.

FIG. 4 is a bottom plan view of the PC mouse docking station of FIG. 1.

FIG. 5 is a rear elevation view of the PC mouse docking station of FIG. 1.

FIG. 6 is a right elevation view of the PC mouse docking station of FIG. 1, the left side being a mirror image of the right side; and,

FIG. 7 is a front elevation view of the PC mouse docking station of FIG. 1.

The broken lines shown in FIGS. 1, 2, 4, and 7 illustrate portions of a PC mouse docking station that form no part of the claimed design.

1 Claim, 3 Drawing Sheets
